UNITED STATES PATENT OFFICE.

EDMUND MORRIS, OF MICHIGAN CITY, INDIANA.

ART OF AND APPARATUS FOR MANUFACTURING COMPOSITE THREADS FOR WEAVING CHAIR-SEAT FABRICS, &c.

SPECIFICATION forming part of Letters Patent No. 609,452, dated August 23, 1898.

Application filed November 6, 1897. Serial No. 657,680. (No model.)

To all whom it may concern:

Be it known that I, EDMUND MORRIS, a citizen of the United States, residing at Michigan City, in the county of La Porte and State of Indiana, have invented a new and useful Art of and Apparatus for the Manufacture of Composite Threads for Weaving Chair-Seat Fabrics, &c., of which the following is a specification.

10 Heretofore split cane has been very largely employed in the manufacture of chair-seats, chair-backs, &c., and there has been no satisfactory substitute for this material so far as I am aware. Split cane is imported and 15 is quite expensive. It is necessary to splice the cane in order to obtain indefinite lengths for rapid weaving. I have discovered that a suitable substitute for cane may be produced in indefinite lengths by properly treating 20 fibrous materials, such as paper and textile fabric, and combining these with a strengthening strand or filament, such as wire.

In my application for patent filed November 6, 1897, Serial No. 657,679, I have described in detail the composite material which 25 I have invented. The present application is confined to the art and apparatus for the manufacture of such material, which, briefly stated, consists of a filament or wire of good 30 tensile strength covered with fibrous material, such as paper, and an interposed layer of muslin or other textile material. The muslin is sized with glue or other hardening material, and the paper strips are cemented to 35 the muslin and inclose the wire. Silicate of soda or other polishing material is used to give to the threads a glaze or polish resembling the natural glaze of cane, while a coating of varnish may be employed to preserve 40 the silicate of soda when this material is used and give finish to the threads or fabric.

In the accompanying drawings, Figure 1 is a diagram of the apparatus which I employ for treating, assembling, and uniting the materials of which the threads are composed. Fig. 2 is a rear elevation of the assembling and compressing rolls. Figs. 3 and 4 are detail views of the wire-guide. Fig. 5 shows a longitudinal central section of the machine 45 for slitting a gang of connected threads into individual threads. Fig. 6 shows a front ele-

vation of the slitting-machine. Fig. 7 is a detail view in section, on the line 7 7 of Fig. 5, of the guides of the slitting-machine. Fig. 8 shows a cross-section of a gang of connected 55 threads produced by the assembling and compressing rolls, and Fig. 9 shows a cross-section of one of the threads on a larger scale.

The apparatus, preferably, is made to work on strips of paper and cloth about six inches 60 wide. The paper is fed from rolls A and B, while the textile fabric C is led from a similar roll, (not shown,) and the wire is led from individual spools, (also not shown in the drawings.) The paper may be Manila or jute paper, that drawn from the upper roll being 65 preferably thicker or heavier than that drawn from the lower roll. The cloth employed is preferably muslin, and a sufficient length of this material is prepared by first sewing together several pieces or bolts and then passing 70 them through a bath of melted glue, whence it is led between pressure-rollers, which serve to press out all superfluous glue, leaving the required amount in the fabric, 75 which is then spread upon a rack to dry. This drying results in a shrinkage of about ten per cent. in the width of the cloth. After being dried the cloth is cut into strips of about the same width as the paper and is 80 wound on rolls. The apparatus for sizing the fabric is not herein shown, as the specific apparatus employed is not important and forms no part of my present invention. As many wires are employed as are necessary to 85 form strengthening-filaments for each of the threads of the gang of threads produced.

The assembling and compressing machine shown consists of an upper roll D and a lower roll D', supported, respectively, in upper journal-boxes d and lower boxes d'. The lower boxes d' rest on a bed-plate D², from which rise standards D³, between which the boxes are arranged. The upper boxes d are free to move vertically, and are guided by suitable 90 guides d³. The lower roll D' rests in open bearings in the boxes d', while the upper roll has no lower bearings, but moves in semicircular bearings in the upper boxes d. The upper boxes d are pressed downwardly to cause 95 pressure between the rolls by means of layers D⁴, pivoted to the standards and extending 100

horizontally across the boxes, upon which they press through the medium of short vertical pins d^4 . Weights D^5 are suspended from the forward ends of the levers D^4 . The upper 5 roll D has its surface formed into closely-joining parallel circular grooves h , concave in cross-section, which are intended to give the proper and usual convex form to the upper side of the threads produced. The lower 10 roll has a similar number of smaller parallel grooves h' formed on its surface, coinciding in position with the grooves h in the upper roll. The object of the grooves h' in the lower roll is to cause the wires to maintain proper 15 positions during the rolling process, the effect being to cause each wire to maintain a middle position in each individual thread. The wires press the lower paper strip down into the grooves, and thus the paper is prevented 20 from being cut by the wires, and ribs are produced on the finished article. If the lower roll were a plane cylinder, the wires would be easily dislodged laterally and mislaid, and any unequal distribution of glue or 25 any bend in the wire would cause such a displacement as to make the product defective.

Upon each of the roller-shafts E, preferably outside of the journal-box, is secured a pressure-collar F. These pressure-collars bear 30 against each other and prevent the surfaces of the rolls from being indented or bruised by contact with each other. The collars are of such diameter as to allow the rolls to approach each other just close enough to form 35 the fabric of the required thickness. Spur-gears G, fixed upon the shafts E, gear the rolls together, and the shaft of the lower roll is extended to receive a pulley or gear-wheel H for communicating power. Guide-bars $II' I^2$, circular in cross-section and having collars i at 40 their opposite ends, are secured to the rear standards D^3 . The two webs of paper and the web of muslin are guided by these bars. A wire-guide J is supported on brackets 45 secured to the front standards. This wire-guide consists of two horizontal plates $j j'$, securely fastened together one above the other. They extend across the machine and are rigidly secured on the brackets J^2 . In the upper 50 side of the lower plate j' is formed a series of wire-guiding recesses or grooves j^3 , which extend across the plate in line with the course of the wires. They fit the wires closely in order that each wire as it issues from its guide 55 shall be directed toward its proper position between the assembling-rolls. The guide J is so disposed as to reach as closely as possible to the meeting-point of the assembling-rolls without touching the paper and cloth, 60 and to facilitate this the forward edges of the plates $j j'$ are beveled, leaving the front edge quite thin. By this arrangement the wires are accurately delivered, each groove j^3 being directly in line with one of the small grooves 65 h' in the lower roll D'. There is a tendency for glue to be squeezed back by the rolls D D' into the grooves j^3 in the wire-guide. If

this glue becomes hard, it will bind the wires and prevent their being fed forward when the machine is started. In order to obviate this, 70 a recess j^4 is planed transversely in the upper side of the lower plate j' , near its forward edge, intersecting all the grooves j^3 . This recess is beveled at its forward side to facilitate stringing the wires through the guides and acts as 75 a drain for any glue that may enter the grooves j^3 , preventing it from passing into the rear portions thereof. The recess j^4 is so close to the forward edge of the plate that the small amount of glue that can be contained within 80 the forward portion of the grooves will not be sufficient to bind the wires. The recess may be cleaned by means of a solution of caustic potash or any other solvent of glue, which may be introduced through the passages j^5 in the top plate j , which lead from 85 holes j^6 in the rear portion of the upper plate. Preferably there are five or six passages, and the solvents will readily pass through them to the recess j^4 , dissolving the glue therein 90 and percolating through the grooves j^3 , and thus effectually cleaning them.

The paper from the roll A is led through devices K for applying glue to its under side. Any suitable devices for this purpose may 95 be employed; but I prefer to use a roller k , mounted in suitable bearings in a steam-jacketed vessel k' . Steam enters the steam-jacket through a pipe k^2 and exhausts through the pipe k^3 . A guide-roller k^4 is mounted in 100 suitable bearings on the top of the steam-box, and the paper passes under this roller before passing over the glue-applying roller k . A similar guide-roller k^6 is mounted on the opposite side of the apparatus, and the 105 paper passes under this roller after having received glue on its under side from the glue-applying roller k . The guide-rollers and the 110 glue-applying roller are revolved very easily and are turned by the passage of the paper, which contacts with them. An adjustable doctor or cleaner k^7 is employed to regulate 115 the amount of glue applied by the roller k to the paper. The gluing devices K' for the lower paper are similar in all respects to the 120 gluing devices K for the upper paper. The lower paper is, however, led through in a slightly-different way, being turned at α about one of the guide-rollers, so that its glued side shall be uppermost and face the glued side of 125 the upper paper.

The wires L are led from individual spools and passed through perforations in a horizontal plate L' ; said perforations being so arranged as to position the wires to permit of 130 their being more easily guided by the guide J. The plate L' is preferably arranged some distance from the pressing and assembling rolls, and the paste-applying devices K K' are arranged at a sufficient distance therefrom to allow the paper to be easily guided to the rolls. The upper paper passes under and in contact with the guide-bar I, and the lower paper passes over and in contact with the

guide-bar I^2 , the wire-guide J being interposed between the two paper webs. As before explained, the sizing and drying of the muslin result in considerable shrinkage thereof, and this shrinkage is quite uneven. The inequalities show themselves in numerous wrinkles in the dried cloth, so that in this form it would be very difficult, if not impracticable, to feed the cloth in a straight course between the assembling-rolls. This uneven shrinkage is probably due to some slight and unavoidable lack of uniformity in the distribution of the sizing-glue. The unsoftened fabric, being more or less rigid and unyielding, does not run truly. It cannot conveniently be pulled sidewise to adjust it as it approaches the roll, and the wrinkles are sometimes so numerous that it is very difficult to slit a bolt of the stuff into strips that are straight. This would of course add to the difficulty of feeding the cloth in a dry state through the rolls. Moreover, the glue in hardening the cloth gives it quite a rough body and surface, the meshes of the cloth being filled with hardened glue, which stands out quite prominently. The paper to which the muslin is attached is softened by the application of the wet warm melted glue, and if it were rolled heavily upon the rigid dry cloth a rough surface would be imparted to the outer side of the soft paper. This will result in an imperfect product, as it is highly important that the threads be as smooth as possible in order to properly imitate cane. In order to overcome these difficulties, I provide means for softening the sized muslin during its passage toward the assembling-rolls. The softening devices M consist of a heating-box m , having horizontal openings m' in opposite ends near the top. Steam is supplied to the box through a pipe m^2 , and steam may exhaust through the openings m' . Water of condensation may escape through a pipe m^3 . A number of parallel horizontal wires m^4 are disposed lengthwise within the box just below the level of the cloth-openings, upon which the cloth rests during its passage. These will prevent the cloth from dragging along the bottom of the box, which may at times contain condensed steam. At the forward end of the box is journaled a roller m^5 , which supports the cloth in its passage and prevents the glue from being scraped off by the lower edge of the opening in the box. From the roller m^5 the cloth passes over the guide-bar I' to the assembling-rolls. The steam softens the sized cloth, so that it is very flexible and pliable and capable of much more compression than if it were dry. It can be guided laterally by an attendant when necessary, being easily pulled diagonally or cornerwise, like any piece of thin textile material. This would not be practicable if the material were dry. The sized muslin is connected with the paper strips while the glue on the paper and the muslin is soft, and a firm union is effected by means of the assembling and com-

pressing rolls. When united in this way, the paper covering is not marked in any way by the meshes of the muslin.

70

It will be observed that the heating devices M and the gluing devices $K K'$ are all situated some distance from the assembling-rolls. This is for the purpose of giving the paper time to swell and the softened cloth time to stretch before they are rolled together. If the strips of paper were rolled too soon after applying the glue, they would continue to swell or stretch after being united, and this would result in forming loose places or blisters where the materials had come apart soon after being glued. This is true also of the cloth. By locating the softening devices and the gluing devices at proper distances from the assembling-rolls these objections are avoided and the product is perfectly even. I have, however, obtained fairly good results where the cloth is led through a bath of glue to size it and then fed at once between the assembling-rolls. This is not nearly so good as the other way described, for in this case the glue would be very soft and would be squeezed backward and out by the rollers, thereby rendering the fabric deficient in glue, and consequently in hardness. The best results are obtained where the hardened glue in the sized cloth is softened (not dissolved) by the steam.

95

I have described the best ways of applying glue to the paper and to the cloth; but I consider as within the scope of my invention other means of accomplishing the same purpose, and the materials for gluing, cementing, and sizing the paper and the cloth may be varied, and the softening devices should be modified to correspond with the kind of sizing material employed.

100

The paper, cloth, and wire are assembled and compressed by the rolls $D D'$, and the fabric X , which results from the compressing operation, is of the form shown in Fig. 8. It consists of a gang of parallel threads, each one of which in cross-section resembles ordinary cane. The threads are all connected together by shallow webs, and each thread, as shown in Fig. 9, is curved on its upper side. On its lower side it is straight or flat for the most part, but has a central rib z . The lower-paper strip is indicated at z' , the upper strip at z^2 , the muslin at z^3 , and the wire at z^4 . It will be observed that the wire projects part way into the rib z and is completely inclosed.

110

The fabric is damp when it emerges from the rolls, and it should be rolled up and thoroughly dried before it is cut up into threads. For slitting the fabric into individual threads I employ the apparatus shown in Figs. 5, 6, and 7. Preferably this apparatus, as shown, consists of two horizontal shafts $N N'$, journaled in standards O , mounted on a bed-plate O' . The shafts are geared together, and the lower shaft is extended to receive a pulley P' , to which power may be applied. Upon the upper shaft N is fitted a series or gang of ro-

125

130

ary cutters Q , and upon the lower shaft is a corresponding gang of cutters Q' . All of these cutters are of the same thickness or width, and this width corresponds exactly with the width 5 of the single cane-thread produced. The cutters are so disposed that the peripheries of one series intersect or overlap the peripheries of the other in order to shear the fabric. The cutters of each gang are separated from 10 one another by collars q , interposed between them, said collars being of the same width as the cutters and of the same width as the threads produced. The fabric is fed forward between the cutters, and it is separated into 15 individual threads, which are wound upon spools. The faces of the cutters Q of the upper series are grooved at q' to fit the convex upper sides of the threads in order to prevent any distortion or marring of the surface 20 of the threads, and the faces of the lower cutters are grooved at q^2 for the passage of the ribs z , which contain the wires z^4 . The grooves q^2 are preferably somewhat larger than the ribs usually required, so as to give plenty of 25 room in case the wires should be slightly displaced. The grooves in the upper cutters may be more concave than is required to fit the threads, so that the fabric shall be pressed upon by the cutters only on the lines where 30 it is to be cut—that is to say, the cutters are so constructed that they do not press upon all points of the fabric, but only on the thin webs between the individual threads.

It is important that the fabric be guided 35 very correctly with reference to the slitting-cutters, so that it shall be cut only along the thin webs between the threads. For this purpose I employ a guide R , constructed as follows: A guide-bar r is arranged transversely 40 in rear of the cutters and is supported on standards r' , mounted on the bed-plate O' . The lower side of the guide-bar r is corrugated, as shown at r^2 in Fig. 7, to permit the passage of the fabric. Below the guide-bar 45 r is arranged another guide-bar R' , which is pivoted at r^3 to the standards r' . This guide-bar has rearwardly-projecting arms r^4 , to which are attached springs r^5 , connected also with the bed-plate O' . The upper front edge 50 of the bar R' is corrugated, as shown at r^6 in Fig. 7, the arrangement being such as to permit the corrugated fabric to pass through and between the guide-bars in a straight line, each individual thread passing through individual 55 corrugations r^2 r^6 in the guide-bars. These corrugations, however, are made slightly larger than the threads, so as not to exert pressure thereon; but are sufficiently small to prevent the threads from being dislodged. 60 The pressure exerted by the springs r^5 is not such as to cause the guide-bars to bite or unduly press the fabric, but is merely sufficient to keep the bars together and keep the threads in line and to permit the bars to yield to accommodate any slight inequalities in the fabric. 65 By this machine the gang of connected threads is slit up into individual threads of uniform

width. These threads are then preferably treated with a finishing or polishing material, such as a solution of silicate of soda, which 70 for this purpose is preferably of a density of about 30° Baumé. The paper becomes filled with the polishing material, and is thereby rendered quite hard and is adapted to resist the wear which it is to receive in a chair-seat. 75 The coating is quite similar to the coating of ordinary cane. Sulfate of potash or other hardening or polishing material might be used instead of silicate of soda; but for many reasons silicate of soda is the preferred material. 80 In order to protect the silicious coating when such is used, varnish may be applied to the material either before or after it is woven. Such varnish not only affords a hard coating, but also prevents the silicate of soda from 85 being attacked by the gases in the atmosphere.

The material produced by my invention is claimed in my application for patent filed November 6, 1897, Serial No. 657,679, while 90 the rotary cutters or slitting-machine shown in Figs. 5, 6, and 7 of the accompanying drawings is claimed in my application for patent filed November 12, 1897, Serial No. 658,327.

I claim herein as my invention—

1. The art of manufacturing threads for weaving, consisting in uniting together by pressure, strips of paper treated with an adhesive substance, a strip of sized textile material and a strengthening-filament. 95

2. The art of manufacturing threads for weaving, consisting in uniting together by pressure, strips of paper treated with an adhesive substance, a strip of sized textile material and a strengthening-filament, and then 105 treating the material with a coating to glaze or harden it.

3. The art of manufacturing threads for weaving, consisting in sizing a strip of textile material, applying an adhesive substance to 110 strips of paper, then softening the sized material, then uniting the paper and textile material to a strengthening-filament and then compressing the combined materials into form. 115

4. The art of manufacturing threads for weaving, consisting in sizing a strip of textile material, applying cementing material to strips of paper, then softening the sized fabric, assembling the paper, fabric and a strengthening-filament, then compressing the assembled materials to unite them and give to them the proper form. 120

5. The art of manufacturing threads for weaving, consisting in sizing a strip of textile material, applying cementing material to strips of paper, then softening the sized fabric, assembling the paper, fabric and a strengthening-filament, then compressing the assembled materials, uniting them and giving to 125 them the proper form, and then treating the formed material with a glazing substance to harden and finish it. 130

6. The herein-described apparatus for the

manufacture of threads for weaving, comprising grooved compressing-rolls, cement-applying devices, softening devices, means for supplying paper past the cement-applying devices to the compressing-rolls, means for supplying sized textile fabric through the softening devices, and means for operating the rolls to unite, compress and give form to the materials.

10 7. The herein-described apparatus for the manufacture of threads for weaving, comprising grooved compressing-rolls, cement-applying devices, softening devices, means for supplying paper past the cement-applying devices to the compressing-rolls, means for supplying sized textile fabric through the softening devices to the compressing - rolls, means for operating the rolls to unite, compress and give form to the materials, and

20 means for supplying a strengthening-filament, such as wire.

8. The herein-described apparatus for the manufacture of threads for weaving, comprising grooved compressing-rolls, cement-applying devices, softening devices, means for supplying strips of paper to the compressing-rolls, means for supplying sized textile material through the softening devices to the compressing-rolls, means for supplying a plurality of strengthening - filaments, such as wire, guides for directing the wires individually, and means for operating the rolls.

9. The assembling, compressing and feeding rolls herein described, the upper one of which has a concave peripheral groove and the lower one of which has a peripheral groove much smaller and narrower than the groove in the upper roll but arranged under it and in line with its middle portion.

40 10. The assembling, compressing and feeding rolls herein described, the upper one of which has a series of concave peripheral grooves and the lower one of which has a corresponding series of peripheral grooves, much

smaller than the grooves in the upper roll, 45 but arranged beneath them and in line with their middle portions.

11. The combination with the grooved feeding and compressing rolls, of means for supplying strips of fibrous material thereto and 50 a wire-guide having grooves or channels for directing the wires individually.

12. The combination with the grooved assembling, compressing and feeding rolls of a wire-guide having individual grooves at its 55 front ends and a transverse groove in rear of said guiding-grooves.

13. The wire-guide herein described, having a tapered front end and formed with a series of longitudinal grooves and with a transverse groove in rear of the first-mentioned groove, and having also channels, j^5 , for supplying cleansing material to the transverse groove.

14. The combination of the compressing- 65 rolls, one of which has a series of peripheral concave grooves and the other of which has a series of peripheral grooves smaller than those of the upper roll but arranged opposite their middle portions, means for supplying 70 material to the rolls and a wire-guide having a series of longitudinal grooves arranged opposite the grooves in the lower roll for directing the wires thereto.

15. The combination of the assembling, 75 compressing and feeding rolls, cement-applying devices arranged at a distance from the rolls, softening devices also removed from the rolls, guides for guiding fibrous material from the cement-applying devices and the softening devices to the rolls, and a wire-guide having its front end close to the body of the rolls.

In testimony whereof I have hereunto subscribed my name.

EDMUND MORRIS.
